UNITED STATES PATENT OFFICE.

JOHN W. DWIGGINS, OF FRANKTON, INDIANA, ASSIGNOR OF ONE-HALF
TO LEROY URMSTON, OF SAME PLACE.

DESIGN FOR A FENCE-PANEL.

SPECIFICATION forming part of Design No. 23,957, dated January 22, 1895.

Application filed August 13, 1894. Serial No. 520,214. Term of patent 3½ years.

To all whom it may concern:

Be it known that I, JOHN W. DWIGGINS, a citizen of the United States, residing at Frankton, in the county of Madison and State of Indiana, have invented and produced a new and original Design for a Fence-Panel, of which the following is a specification, reference being had to the accompanying drawing, forming part thereof.

10 The figure is a view of a fence panel embodying my design.

The leading features of my design consist of a series of diamond shaped interstices which are alternately traversed by the horizontal wires e'' , e''' , and perpendicular wires B, thus forming in connection with the horizontal wires e' and e'''' , a series of squares; and a series of circular loops E, extending above the horizontal wire e' , at regular intervals. In 20 the squares formed by the horizontal wires e''

and e'''' , and the perpendicular wires B, is a perfect diamond shaped opening a, while the squares directly beneath the diamond shaped opening are traversed perpendicularly by the wire D. Circular loops b, surmount 25 the horizontal wire e'' , at a point half-way between the perpendicular wires B.

The effect of my design viewed in elevation as in the figure is that of a series of right and left oblique wires, crossed at regular intervals by horizontal and perpendicular wires at right angles to each other, the upper horizontal wire surmounted by a series of loops.

What I claim is—

The design for a fence panel, as herein 35 shown and described.

JOHN W. DWIGGINS.
